UNITED STATES PATENT OFFICE.

LOUIS HENRI LIBERT BELLEM AND GASTON JEAN-BAPTISTE BRÉGÉRAS, OF NEUILLY-SUR-SEINE, FRANCE.

INTERNAL-COMBUSTION ENGINE.

1,157,287.

Specification of Letters Patent. Patented Oct. 19, 1915.

Application filed March 2, 1912. Serial No. 681,115.

To all whom it may concern:

Be it known that we, LOUIS HENRI LIBERT BELLEM and GASTON JEAN-BAPTISTE BRÉGÉRAS, citizens of the Republic of France, and residents of 60 Boulevard d'Asnières, Neuilly-sur-Seine, Seine, in the said Republic, have invented a new and useful Improvement in Internal-Combustion Engines, of which the following is a specification.

- 10 This invention relates to improvements in internal combustion engines in which oils of low volatility are used, especially heavy petroleums, and more particularly in such internal combustion engines as described in
15 our prior United States Patent No. 513261, of August 17th 1909, in which the atomization of liquid petroleum is obtained by pulverization of said combustible by the action of the vacuum produced in the cylinder.
20 For this purpose in the engine described in our said patent, the liquid combustible suitably pulverized was admitted into the cylinder at the beginning of the suction stroke, while the air for the combustion was only
25 supplied at the end of said suction stroke.

The present improvements consist in modifying the mode of admission of the air for the combustion in the engine at the end of the suction stroke, using for the purpose an operated valve opening in the top of the cylinder, and on the other part in placing the atomizer in front of this valve in order to increase the action of the vacuum in the cylinder and to introduce at the same time in this cylinder the pulverized petroleum and the air of combustion at the end only of the suction stroke.

In the accompanying drawings, Figure 1 is a vertical section of the top part of our improved engine. Fig. 2 is a similar view partly in section showing a modification which may be employed in certain cases where the atomizer consists of a spraying nozzle of a well known type.

45 As will be seen in Fig. 1, in the head of the cylinder *a* a pipe *b* opens, the interior opening of which is controlled by the admission valve *c* placed in a known manner opposite the discharge valve *d*. The valve *c* is operated by a two-armed lever *e* acting on its stem *f* and suitably operated by the cam shaft of the engine in order to open at the end of the suction stroke; a spring tends to draw constantly this valve into its closed position. The outer end of the pipe *b* open-

ing in the atmosphere is controlled by a throttle valve *h* which may be operated from outside and allows of opening or closing this pipe more or less. In the pipe *b* in front of the admission valve *c* is mounted the petroleum atomizer, which consists in this case in a pulverizing valve *i* of the kind described in our said prior patent. It will be seen that owing to this arrangement by the downward stroke of the piston *j* during the suction stroke, a vacuum will be produced in the cylinder the more considerable as the valve *c* remains closed. At the end of the suction stroke this valve opens suddenly under the action of its controlling means and the vacuum can thus act energetically in the passages of the pulverizing valve *i* in order to secure a perfect atomization of the petroleum in the manner described in our said patent. In starting the engine care should be taken that the throttle valve be shut in order to increase the action of the vacuum; after starting, the throttle valve must be opened to the proper extent in order that together with the atomized petroleum admitted through the pulverizing valve *i* the quantity of air necessary for its combustion may be admitted in the cylinder.

In the case where it would not be necessary to produce the direct starting of the engine by means of the heavy petroleum and where there would be no drawback in the use of gasolene, benzine or other combustible to start the engine, a pulverizing nozzle *k* of a well known type, such as the spraying nozzle of a carburetor supplied by a float chamber *l*, could be substituted for the atomizing valve, as shown in Fig. 2. It may be desirable in that case to provide the pipe *b* with a cock *m* for the admission of gasolene or other volatile combustible in order to allow the quantity of gasolene or other volatile combustible necessary for starting the engine to enter. After the starting has been effected, the action of the great vacuum produced in the cylinder will sufficiently atomize the petroleum delivered through the spraying nozzle *k*, and will thus allow the engine to continue its normal running by the use of this single combustible, to wit: petroleum.

What we claim is:

1. In an internal combustion motor using fuel of low volatility, the combination of a cylinder, a piston therein, an intake passage

opening into the top of the cylinder; an inlet valve at the mouth of the said passage, and an atomizer located in the said passage ahead of the valve and adapted to operate under the influence of a vacuum, the said valve being arranged to open only when the piston is at the end of its intake stroke in order to create a vacuum in the cylinder.

2. In an internal combustion motor using fuel of low volatility, the combination of a cylinder, a piston therein, an intake passage opening into the top of the cylinder, a throttle valve in said passage, an inlet valve at the mouth of said passage communicating with the cylinder, an atomizing valve located in said passage intermediate the throttle valve and inlet valve and adapted to operate under the influence of a vacuum, the said inlet valve being arranged to open only when the piston is at the end of its intake stroke in order to create a vacuum in the cylinder.

tle valve and inlet valve and adapted to operate under the influence of a vacuum, the said inlet valve being arranged to open only when the piston is at the end of its intake stroke in order to create a vacuum in the cylinder, and an exhaust valve in said cylinder. 20

In testimony, that we claim the foregoing as our invention we have signed our names in presence of two witnesses, this nineteenth day of February, 1912. 25

LOUIS HENRI LIBERT BELLEM.
GASTON JEAN-BAPTISTE BRÉGÉRAS.
